UNITED STATES PATENT OFFICE.

EDWIN C. DONNELL, OF BROCKTON, MASSACHUSETTS.

INNERSOLE.

1,152,887.

Specification of Letters Patent.

Patented Sept. 7, 1915.

Application filed April 9, 1915. Serial No. 20,185.

To all whom it may concern:

Be it known that I, EDWIN C. DONNELL, a citizen of the United States, and resident of Brockton, in the county of Plymouth and State of Massachusetts, have invented certain new and useful Improvements in Innersoles, of which the following is a specification.

This invention relates to an inner sole for a welted shoe having an inseam stitch-engaging lip formed separately from and attached to the body of the sole.

The invention has for its object to provide an improved construction of the sole body and the lip whereby a strong, substantial and durable water-proof sole may be produced at a minimum cost both for material and labor.

The invention consists in the improvements which I will now proceed to describe and claim.

Of the accompanying drawings forming a part of this specification: Figure 1 represents a plan view of an inner sole embodying my invention; Fig. 2 represents a section on line 2—2 of Fig. 1; Fig. 3 represents a plan view of a portion of the intermediate layer hereinafter referred to; Fig. 4 represents an enlarged section on line 4—4 of Fig. 3; Fig. 5 represents a fragmentary sectional view on an enlarged scale showing the layers of which the sole body is composed as they appear before the body is grooved; Fig. 6 represents a view similar to Fig. 5, showing the body grooved; Fig. 7 represents a transverse section showing the strip from which the inseam stitch-engaging lip is made; Fig. 8 represents an enlargement of a portion of Fig. 2; Fig. 9 represents a view similar to Fig. 8, showing a modification; Figs. 10 and 11 represent sectional views showing another modification.

The same reference characters indicate the same or similar parts in all the views.

In making my improved inner sole I proceed preferably as follows: I provide a sole-shaped layer 12 of material which is compressible and preferably absorbent, the best material of which I am aware being the fabric known as buckram, and composed of relatively coarse and loosely woven warp and weft threads, this material possessing a desirable degree of tensile strength, and being relatively thick, so that it may be readily indented to form the groove hereinafter de-

scribed. To one side of the layer 12, which I call the intermediate layer, I cement a facing layer 13 of relatively thin woven textile fabric, preferably the cotton fabric known as sheeting or light duck. I then apply indenting pressure to the incomplete body formed by the assembled layers 12 and 13, in such manner as to form an elongated groove 14 extending from a point near the heel end and near one edge of said body to a corresponding point near the heel end and near the opposite edge of said body, both ends of the groove being shown by Fig. 1. The groove extends continuously from one of the ends shown by Fig. 1 substantially parallel with the margin of the body and along the shank portion, the fore portion and the toe portion, the groove being separated from the margin by a space which determines the width of the usual feather portion provided between the inseam stitch-receiving lip hereinafter described, and the margin of the body. Said feather portion may vary in width, if desired, and may be wider at the shank portion of the body than elsewhere. The indenting pressure is exerted on the facing layer 13 while the intermediate layer 12 is supported by a flat surface, so that the groove is formed by indenting and compressing both layers, the compression being mainly effected in the relatively thick and compressible layer 12, as indicated by Fig. 6. I prefer to apply coatings 12^a of waterproofing material, such as gutta percha, to the sides of the layer 12, said material being absorbed more or less by the absorbent material of said layer, and not only waterproofing the layer, but also increasing its conformability to the indenting pressure, so that the groove formed as described is permanent. I next attach to said incomplete body an inseam stitch-engaging lip, composed of an elongated strip 16 which may be made of leather having a grain side 16^a, or other suitable material. Said strip is preferably centrally reduced in thickness by a longitudinal groove 17 formed midway between its edges, and is united to the incomplete body formed by the layers 12 and 13 by stitches 18 passing through the reduced central portion of the strip 16 and the grooved portions of the layers 12 and 13, the surface portions of said stitches being laid in the groove 17, and on the outer side of the layer 12. The strip 16, when in temper, is bent, as indi-

located in the groove 14.

located in the groove 14. The groove 17 enables the strip 16 to be bent without causing its neck portion to bulge outwardly, so that no part of said neck is wider than the combined thickness of the lip members. Said groove also serves to additionally depress the stitches 18.

15 The sole body is completed by cementing to the intermediate layer 12 another sole-shaped facing layer 20, which may be composed of thin leather, and is preferably split leather. The facing layer 20 conceals the stitches 18. 14 forms a depressed seat for

20 The groove 14 forms a depressed seat for the neck of the lip formed by the bent strip 16, so that the stitches 18 are located well below the path of the needle which forms the usual inseam stitches 22 during the operation of stitching a welt and an upper to the lip of the inner sole, hence the stitches 18 cannot be cut or injured by the said needle, nor by an awl employed to form holes for the inseam stitches.

25

30 The compressibility of the intermediate layer 12 adapts the sole to be indented to form the groove 14, and the porosity of said layer renders it an effective holder for the waterproofing material.

35 If desired, a layer 23 of canvas may be interposed between the intermediate layer 12 and the facing layer 20, as shown by Fig. 9. Figs. 10 and 11 illustrate a modification

Figs. 10 and 11 illustrate a modification in which the body 24 of the inner sole is composed of a single piece of leather having a groove 14^a cut in one side and a channel 25 cut in its opposite side to receive the stitches 18 which connect the lip forming strip 16 with the body.

45 Having described my invention, I claim:
An upper sole comprising a body hav-

1. An inner sole comprising a body having a groove in one side spaced from and following the contour of its margin, an inseam stitch-engaging lip composed of an elongated strip folded longitudinally to form two lip members arranged side by side and a bent neck connecting said members and seated in said groove, and stitches uniting said strip with the body and passing through the neck of the strip, said stitches being depressed by the seating of the neck in the groove, below the points where the usual inseam stitches pass through the lip.

60 the lip.
2. An inner sole comprising a body hav-

uniting said strip with the body and passing through the neck of the strip, said stitches being depressed by the seating of the neck in the groove, below the points where the usual inseam stitches pass through the lip, the strip being grooved to additionally depress the neck-engaging stitches and prevent the neck from bulging laterally. 70 75

3. An inner sole comprising a body made up of superimposed layers including facing layers and an intermediate layer of compressible material, said body having an indented groove in one side spaced from and following the contour of its margin and formed in one of the facing layers and the intermediate layer, an inseam stitch-engaging lip composed of an elongated strip folded longitudinally to form two lip members arranged side by side, and a bent neck connecting said members and seated in said groove, and stitches uniting said strip with the body and passing through the neck of the strip, one of the facing layers, and the intermediate layer, said stitches being covered by the other facing layer, and depressed by the seating of the neck in the groove, below the points where the usual inseam stitches pass through the lip.

2 pass through the lip.
9 4. An inner sole comprising a body made
n up of superimposed layers including facing
is layers and an intermediate layer of com-
g pressible material, which is also absorbent,
el said body having an indented groove in one 100
ne side spaced from and following the contour
ag of its margin and formed in one of the fac-
ing layers and the intermediate layer, the
sides of the intermediate layer being more or
v less impregnated with a waterproofing ma-
nd terial having also the capacity of render-
n ing the groove permanent, an inseam stitch-
an engaging lip composed of an elongated strip
to folded longitudinally to form two lip mem-
de bers arranged side by side, and a bent neck 110
ers connecting said members and seated in said
nes groove, and stitches uniting said strip with
ss the body and passing through the neck of
aid the strip, one of the facing layers, and the
of intermediate layer, said stitches being cov- 115
ered by the other facing layer.
whereof I have affixed my

In testimony whereof I have affixed my
signature.

EDWIN C. DONNELL.
